DESIGN FOR A CHAIR

William N. Brazauski, Chicago, Ill.

Application August 30, 1947, Serial No. 141,129

Term of patent 14 years

(Cl. D15—1)

To all whom it may concern:

Be it known that I, William N. Brazauski, a citizen of the United States, residing at Chicago, in the county of Cook and State of Illinois, have invented a new, original, and ornamental Design for a Chair, of which the following is a specification, reference being had to the accompanying drawing, forming part thereof.

I claim:

The ornamental design for a chair, substantially as shown.

WILLIAM N. BRAZAUSKI.
